SPRAY NOZZLE

Louis O. French, Milwaukee, Wis.

Application September 20, 1935, Serial No. 41,361

11 Claims. (Cl. 299—107.3)

The invention relates to spray nozzles and more particularly to a fuel injection nozzle for spraying fuel into the cylinder of an internal combustion engine or into a passage communicating with the cylinder, said nozzle being of the check-valve-controlled type.

With the usual check-valve-controlled fuel nozzles the space between the valve and the nozzle is so large that the fuel pressure is reduced before delivery and this produces a poor spray and frequently causes dribbling and cannot be used with any atomizing effect on small bore engines. Where the valve itself has been caused to move outwardly against a nozzle member, the bulk of the fuel charge may be discharged through the nozzle during the time that the valve is moving to a nozzle engaging position and as the valve closes there is a relatively large open or clearance space between the valve and the nozzle from which dribbling may occur. One object of the present invention is to provide a spray nozzle that will overcome the above mentioned difficulties and produce a spray equaling that of the more complicated and costly differentially operated needle valves by having the valve contact with the nozzle member at all times, the nozzle member also protecting the valve so that carbon deposits cannot reach its seating surfaces as is sometimes the case with needle valves, and in this connection the present invention may be considered a continuation in part of my application Serial No. 754,057, filed November 21, 1934.

A fuel injection valve has to perform a most exacting service. In the case of injectors for separate pumps the valve should close promptly after each injection to avoid erratic action and prevent dribbling. In the case of injectors in which the fuel is put under pressure in the injector itself by a plunger working therein the injector valve becomes the discharge valve of the pump, and if it does not close promptly or properly, it will admit air or gas fumes and prevent proper metering of the fuel to the engine cylinder and may cause dribbling. After considerable experimenting, I have found that a rigid check valve seating against a rigid seat, rigidly supported and preferably positively guided relative to said seat, is the least apt to get out of order. Such valves per se are not new, but the problem has been to combine with such a check valve and its seat a means to close the valve and allow it to open under the action of fuel pressure which will keep the fuel discharge passage or passages short and provide a spray with a clean cut off and one whose characteristics are determined inde-

pendent of the valve opening. Furthermore, according to the present invention the means to close the valve also protects the valve seat from carbon deposits getting into it from the engine cylinder. 5

A further object of the invention is to provide a check-valve-controlled spray nozzle in which the valve is closed by a separate resilient nozzle member which is initially tensioned by a part on either the valve or nozzle member which on the assembling of the parts acts to tension said member. In the preferred embodiment of the single jet nozzle the tensioning part is grooved to conduct fuel to the discharge passage for the nozzle and preferably so as to determine in general the spray 15 characteristics so that the discharge passage may be relatively large.

A further object of the invention is to provide a check-valve-controlled spray nozzle in which the valve has a flat face engaging a flat seat at the 20 end of the injector casing or a renewable part secured thereto, said seat preferably being raised or coextensive with the surface of said end or part so that it and the valve may be readily inspected and cleaned, the passage or passages for conducting 25 the fuel from the valve opening to the discharge passage in the nozzle member also being readily accessible for cleaning when the valve is taken apart.

A further object of the invention is to provide 30 a check-valve-controlled spray nozzle that may be readily adapted for different forms of sprays depending upon whether the valve engages or projects through the discharge opening in the nozzle or engages a multiple spray nozzle tip. 35

The invention further consists in the several features hereinafter set forth and more particularly defined by claims at the conclusion hereof.

In the drawing:

Fig. 1 is a vertical sectional view through a 40 spray nozzle embodying the invention;

Fig. 2 is a plan or head end view of the valve shown in Fig. 1;

Fig. 3 is a view similar to Fig. 2 showing cer- 45 tain modifications;

Fig. 4 is a view similar to Fig. 1 showing certain modifications, parts being broken away;

Fig. 5 is a view similar to Fig. 1 showing certain modifications, parts being broken away; 50

Fig. 6 is a top plan view of the valve closing member shown in Fig. 5;

Fig. 7 is a detail vertical sectional view simi- 55 lar to Fig. 1, showing certain modifications, parts being broken away;

Fig. 8 is a top plan view of the valve shown in Fig. 7;

Fig. 9 is an enlarged elevation view of the valve shown in Fig. 7 with parts broken away and parts shown in section.

Referring to Figs. 1 to 4, the numeral 10 designates a casing provided with a fuel supply passage 11 having a threaded end 12, for connection with a pipe or pipe fitting by which fuel is conducted from any suitable pressure pump, and a threaded part 13 for mounting the injector in the engine, or in the intake conduit thereof.

A plain flat surface 14 is either formed at the end of the casing or on a member 15 secured in fluid tight engagement with said end, said seat surrounding a valve guide passage 16. The seat is a rigid or non-flexible part, rigidly supported. A separate seat member 15 is preferred as it may then be made of material best suited for the purpose and be replaceable at a relatively small expense.

25 A flat faced check valve 17 is adapted to engage said surface and has a stem positively guided in the passage 16. While the working clearance between the stem and its guide may be sufficient for passage of fuel therebetween, said valve may be fluted or grooved as at 19 to conduct the fuel to an annular groove 20 adjacent its seating face. It is provided with an end 21 whose dimensions may vary but which in most cases is smaller than the seating area 30 so as to localize its contact with a valve closing or retainer and nozzle member 22 which is clamped to the seat as hereinafter described.

35 The nozzle and closing member 22 is in the form of a cylindrical member having a plain upper surface 23 and a central opening 24 and formed of steel or suitable alloy steel and adapted to flex and act as a closure spring for the
40 valve 17 with which it contacts, this contact preferably not depending upon any special centering projection between said valve and spring. The member 22 is anchored at its outer edge to the casing by the inwardly flanged clamping nut 25
45 which is in threaded engagement with the lower end of the casing 10. Said member 22 might be clamped directly to the member 15 as where the seating surface 14 for the valve is on said member 15 and inset so as to accommodate the main
50 valve head and a portion of said end 21, but in order to facilitate access to the seat so that it may be readily inspected and cleaned the seating surface is either raised or made coextensive with the outer end of the part on which it is
55 formed and a filler member 26 preferably having good sealing qualities such as brass, bronze, or copper is interposed between the seat member and the closing member 22 and is of a thickness less than the total depth of the valve head so that when said members 22 and 26 are clamped together and against the seat member or end of the casing said member 22 will be put under a
60 predetermined initial tension and exert this upon the valve 17 to hold it against its seat. When, however, the pressure of the fuel in the casing 10 reaches a value sufficient to overcome this tension, the closing member will yield and allow the valve 17 to move off its seat and permit fuel
65 to pass through the discharge opening 24.

The end 21 in Fig. 1 is shown as a straight pin, and its height may vary from a few thousandths to about a thirty-second of an inch, and the thickness of the filler member 26 will vary accordingly, and in the case of a very small pin end the thickness of said member 26 may be about

equal to that of the main body portion of the valve head where said portion projects beyond said seat. The relatively longer projection is shown and has the advantage of providing a grip for a hand vise or chuck that may be used in initial grinding or subsequent handling of the valve. Where the valve is of small diameter so that it may be gripped at the larger part of its head, the end may be made conical, as shown in Fig. 4, to reduce the clearance, provide a more stream line approach to the spray opening, and simplify the machining of the valve. 5

Various forms and arrangements of passages may be provided between the valve and its closing member and these, when the discharge opening 24 is relatively large, will determine the character of the spray. For a wide angle spray the end 21 may have a conical recess 27 formed therein with tangentially disposed grooves 28 formed in said end and communicating with said recess 20 as shown in Fig. 2, which recess communicates with the discharge opening 24 and forms a whirl chamber at the upper end of said opening so as to produce a centrifugal type spray whose spreading tendency may be controlled to some extent 25 by the length of said passage 24. For a more concentrated spray the end 21 may have a diametrically extending groove 29 cut or otherwise formed therein as shown in Fig. 3, so that two streams of fuel from opposite directions will meet 30 each other at the upper end of the discharge opening 24 and impacting against each other will produce a well atomized spray even though the diameter of said opening may be relatively large. With either of these nozzle forms the diameter 35 of the discharge opening may be as large as two to three hundredths of an inch, so that it may be cleaned if necessary by a needle or a pin.

In Fig. 5 I have shown the injector valve in that type of injector wherein the casing 30 has a pump barrel 30' mounted therein and shown as supplied with fuel through passages 31 and 32 and having a pump plunger 33 reciprocating therein and in this instance the injector valve is the discharge valve of the pump. 45

A plain seating surface is either formed on the end of the pump barrel or a member 34 may be secured in fluid tight engagement therewith, said member having a valve guide passage 35 alined with the bore of the pump barrel and here shown 50 as having an inset seating face 36.

A flat faced check valve 37 is adapted to engage said surface 36 and has a stem 38 positively guided in the passage 35 and may be fluted and grooved the same as the valve 17 and a slot or groove 39 is formed on the front face of its head of sufficient depth to take a screw driver or other tool or metal part that may be inserted in it for turning said valve to service the same.

In some engines it is usual to provide a plurality of sprays leading at certain predetermined angles from the nozzle tip, and in Fig. 5 I show the valve 37 normally held closed by a separate cylindrical resilient nozzle and closing member 40 of steel or other suitable material having a nozzle tip 41 formed integral therewith or detachably mounted therein as by a flange 42 engaging the main body portion of the member 40 adjacent a centrally disposed opening 43, said tip having a central passage 44 and a plurality of spray passages 45 leading therefrom, said flanged portion being of a height to put the member 40 under a predetermined tension when its outer edge is clamped to the barrel 30 or seat member 34, if used, by the flanged clamping nut 46 in threaded engagement with the barrel 30.

engagement with the casing 29, a washer or filler 47 being interposed between said member 40 and the part to which it is clamped to insure a fluid tight seal. As the slotted surface of the valve 5 abuts against the top of the tip 41, the fuel passing the valve seat enters the passage 44 from the groove 39 and thence proceeds through the spray passages 45 as the initial tension of the closing member 40 is overcome by the action of 10 the fuel pressure on the valve. The tip 41 may also have a single spray opening formed therein if desired.

Where as shown in Figs. 1 and 5 separate seat members 15 and 34 are used, a sealing gasket 48 15 may be interposed between said member and the casing or pump barrel.

In Figs. 7 to 9 I have shown certain features previously mentioned in connection with the other constructions, to wit: a casing 49 having a raised 20 flat valve seat 50 formed thereon at its lower end and having a supply passage 51 in which the stem of the flat faced check-valve 52 is guided. In this instance the valve 52 cooperates with the resilient nozzle and closing member 53 to form a 25 pintle type nozzle, said valve opening against the predetermined tension of said member 53 under the action of fuel pressure and having a pin projection 54 passing into or through the opening 55 in said closing member and spaced therefrom to form an annular orifice. For conducting the fuel to the top or inner end of this orifice the bottom of the valve head is provided with an annular groove 56 adjacent the pin 54 and radially disposed grooves 57 connecting said groove 56 30 with the space surrounding the valve head. The area of the valve head at 58 adjacent the closing member 53 is preferably reduced to localize the pressure on said member at its central portion and said head is also shown as provided with 35 an undercut groove 59 for quick seating.

Since with the pintle type accurate centering is necessary for best spraying effect, the closing member 53 is shown as provided with a flanged 40 edge 60 centered directly on the casing at 61 and held thereagainst by the clamping nut 62 and an annular filler member 63 is loosely mounted between the casing 49 and the closing member 53.

It will be noted that in all the forms shown the nozzle and closing member only rests against 45 the valve and does not in any way act to center the valve relative to its seat, and as a consequence the valve is relieved of any strains from said member that might be imposed upon it tending to partially unseat it, and the nozzle member is 50 free of any strains on the sides of its discharge opening that might tend to rupture it. In the above described constructions the valve is guided to its seat by the guide passage in the member or part forming the seat, and this member or 55 part is rigid and rigidly supported and out of direct contact with the heated gases of the engine. Furthermore, the distance the fuel has to travel from the valve opening to the discharge opening in the nozzle member is so short that substantially 60 the full effect of the supply pressure is attained at the nozzle and the volume of the fuel at the discharge passage is so small that dribbling does not occur.

It is also to be noted that in the forms shown 65 in Figs. 1, 4, and 7 as the valve is opened and closed, it is in constant contact with the nozzle member which also moves with the valve and to some extent transversely to it so that any tendency for carbon to collect and cake up the 70 spray passage or passages is prevented.

All the parts above described are of metal and preferably except where otherwise mentioned a suitable alloy steel. The valves and their rigid seat members may be formed of aluminum steel hardened by nitriding such steel now being com- 5 monly used in this art.

The drawings herein, as to the main parts, are on an enlarged and only an approximate scale and the clearances and size of passages have been greatly exaggerated.

I desire it to be understood that this invention is not to be limited to any particular form or arrangement of parts except in so far as such limitations are included in the claims.

What I claim as my invention is:

1. In a spray nozzle, the combination of a valve, a metal seat member for said valve, and a valve retainer and nozzle member normally holding said valve to its seat, said valve being movable relative to its seat under the action of the pressure of the liquid to be sprayed.

2. In a spray nozzle, the combination of a fluid pressure operated check valve, and a nozzle member constantly acting to hold said valve to its seat and provided with a spray opening, there being a communication between said valve and member.

3. In a spray nozzle, the combination of a rigidly seated and guided fluid pressure operated check valve, and a valve retainer and nozzle member normally holding said valve to its seat, said valve being movable relative to its seat and with a portion of said member under the action of the pressure of the liquid to be sprayed.

4. In a spray nozzle, the combination of a rigid seat member, a movable check valve positively guided by said seat member and cooperating therewith, and a resilient valve closing and nozzle member having a non-centering contact with said valve and normally holding said valve to its seat, said valve being movable relative to its seat under the action of the pressure of the liquid to be sprayed.

5. In a spray nozzle, the combination of a rigidly seated and guided fluid pressure operated check valve, and a valve retainer and nozzle member constantly engaging the head end of said valve and normally holding it to its seat, parts of said member and said valve having a passage formed therebetween determining the spray characteristics of said member.

6. In a spray nozzle, the combination of a rigid seat member, a movable check valve centered with reference to said seat member and cooperating therewith, and a resilient valve closing and nozzle member having a non-centering contact with the head end of said valve and normally holding said valve to its seat, the contacting surfaces of said nozzle member and head of said valve having a discharge passage formed therebetween determining the spray characteristics of said nozzle member.

7. In a spray nozzle, the combination of a rigidly seated and guided fluid pressure operated check valve, and a valve retainer and nozzle member constantly engaging the head end of said valve and normally holding it to its seat, said nozzle member having a relatively large centrally disposed discharge passage, the end of said valve engaging said member adjacent said passage and grooved to determine, in general, the spray characteristics of the fluid passing therethrough.

8. In a spray nozzle, the combination of a rigidly supported rigid seat member having an

opening, a check valve seating on said seat member and controlling the passage of liquid through said opening, a resilient closing member constantly engaging said valve and normally acting to hold it to its seat and provided with an outlet opening, there being an open passage between said valve and said member at their point of contact communicating with the opening in said member.

9. In a spray nozzle, the combination of a rigidly seated and guided fluid pressure operated check valve having a flat exposed end, and a resilient valve retainer and nozzle member having a substantially flat face portion constantly engaging said end and provided with a discharge opening, there being a communication between said valve and member.

10. In a spray nozzle, the combination of a casing, a rigidly seated and guided fluid pressure operated check valve mounted in said cas-

ing and having a flat exposed end, and a centrally apertured substantially flat spring member engaging said end, adjacent its opening, said end having a fluid conveying groove, and means for clamping said member in tensioned engagement with said valve.

11. In a spray nozzle, the combination of a rigidly seated and guided fluid pressure operated check valve and resilient valve retainer and nozzle member constantly contacting said valve and normally holding said valve to its seat and provided with a discharge passage, there being a passage from the seat of said valve to said discharge passage whose length is determined substantially by the thickness of the head of said valve, said valve being movable relative to its seat under the action of the pressure of the liquid to be sprayed.

LOUIS O. FRENCH. 20
